UNITED STATES PATENT OFFICE.

ERNEST L. PATTEN, OF MALDEN, MASSACHUSETTS, ASSIGNOR TO WELLMAN COMPANY,
A CORPORATION OF MAINE.

MACHINE FOR CUTTING SOLES.

1,418,604.

Specification of Letters Patent. Patented June 6, 1922.

Application filed November 7, 1919. Serial No. 336,414.

To all whom it may concern:

Be it known that I, ERNEST L. PATTEN, a citizen of the United States, residing at Malden, county of Middlesex, and State of 5 Massachusetts, have invented a certain new and useful Machine for Cutting Soles, of which the following is a full, clear, and exact description.

This invention relates to machines for cutting sheet material and especially sheet rubber in any desired pattern and preferably with a beveled edge.

It generally aims to include the mechanism disclosed in my prior Patents Nos. 15 1,144,429 and 1,270,819, granted June 29, 1915, and June 25, 1918, respectively, in which for one thing the frame of the machine, carrying a knife, form, leader and other associated parts and their driving 20 mechanisms, is shifted relatively to a stationary work table in order to facilitate the introduction of work. The relative great weight of the frame and associated parts of my prior machines makes their movement 25 or shifting objectionable and undesirable.

The present invention aims primarily to avoid this by a combination and arrangement of parts in which a relatively light table is shiftable to and from the form and 30 knife for facility in introducing work.

Another object of the invention is to provide an improved arrangement of starting levers making the operation of the machine more convenient.

35 Still another object of the invention is to provide means for reliably stamping the material, in the case of a rubber sole, with a character designating its size and preferably such a means as may be operated in one operation with the bringing together of the work table and form to grip the material.

A further object of the invention is to provide for convenient manual operation of the machine whenever it is desirable to run 45 the knife around the form by hand instead of by power.

The invention further aims to provide a new and improved means for locking a leader in position and also for preventing 50 the knife carrying means from tilting during a cutting operation.

In the preferred form of the machine the work is supported on a table which is raised to grip and hold it against the form while 55 a knife is swiftly swiped around the form in

a path approximating the leaders outline and governed by a shiftable carrier and by a shiftable head, which leader and head together control the movement of a driven knife carriage that is linked to an endless 60 chain or other actuating means. The endless chain is driven from a main shaft which is preferably adapted for either power or manual operation, the latter being managed by the provision of a one way clutch or the 65 like operable by a hand crank when the machine is disconnected from power. The work table is normally held spaced from below the form and is adapted to be raised into co-operative gripping relation therewith by a series of links and levers extending to a foot treadle which is preferably provided with a member extending laterally over a second and independent foot treadle that governs the operation of a power clutch 70 through which the machine is power driven. The work table comprises a platform which is bolted to a post slideable in the frame and a table which is secured to the platform by a number of screws that are arranged to permit the plate to be positioned in parallelism with the lower face of the form. A platen is carried by the work table and co-operates with the stamp or die on the lower face of the form.

85 The preferred embodiment of the invention is illustrated in the accompanying drawings in which:

Fig. 1 is a side elevation, of the upper part of a machine of the preferred form.

Fig. 2 is a front elevation of the same partly in section.

Fig. 3 is a side elevation of the lower part of the frame of the machine.

Figs. 4 and 5 are details in plan and front 90 end elevation respectively of one side of a leader and its carrier showing an improved spring detent for locking them together.

Fig. 6 shows a one way clutch partly in section.

Fig. 7 is a view of a form having a stamp or die on its lower face and shows the arrangement of the materials between the form and work table.

Fig. 8 is an elevation of the knife carriage 105 viewed at right angles to the position in which it appears in Fig. 1.

The machine illustrated in the drawings is of the general construction and arrangement shown in the later of my two above 110

mentioned patents, and reference is now made thereto for a full understanding of details of construction that are not herein sufficiently made clear.

- 5 Sheet material 1 with an underlying cutting sheet 2 supported on a work table 3 is gripped and held against a form 4 detachably or otherwise secured as indicated at 5 to a bracket arm 6 which is bolted to an 10 overhanging portion 7 of a frame indicated generally by the numeral 8. A knife 9 is adapted to be moved around the form in contiguity to its periphery. The knife 9 is removably secured to an arm 10 pivoted on 15 the pin 11, which is carried by a plate 12 and a coiled spring 13, normally urges the knife toward the stop 14. Above the knife 9 an anti-friction roller 15 is mounted to take care of lateral strain resulting from the 20 inclined cutting position of the knife. Plate 12 is fixed in the lower end of a spindle 16, which is confined against endwise movement but rotatable in a carriage 17 slidably supported by a truck 18 provided with guide 25 ways 19 confining the carriage 17 to rectilinear movement relative thereto.

The plate 12 to one side of the spindle 16 carries an upright pin 20. By the spindle 16 and pin 20 pairs of friction rolls 21-22 30 and 23-24 are supported in spaced relation to embrace a sinuous flange 25 of a leader 26 which is removably supported in a leader carrier 27 slidably sustained in a groove 28 provided in the arm 29 depending from the 35 frame section 7. The leader carrier is pinned at 30 to a pitman 31 which must be operated by an adjustable crank pin of the construction fully disclosed in my prior Patent No. 1,270,319 above mentioned.

40 The leader carrier 27 is undercut to receive the leader 26 as indicated in Figs. 4 and 5 and is provided with a plurality of flange-like fingers 32 which define with the overhanging portion of the leader carrier a 45 guideway for sustaining the leader 26. To lock the leader and leader carrier together a resilient wire or spring 33 which is anchored at 34 to the leader carrier is passed through a pin 35 sleeved in an apertured stud 36 50 suitably secured to the leader carrier, provision being made for perpendicular movement of the spring 33 and the pin 35 by slotting the stud 36 as indicated at 37. It will be understood that the spring detent thus 55 constituted is operable transversely of the leader in a substantially perpendicular direction into and out of an opening (not shown) in the leader plate to effect a locking or unlocking of the same with relation to the 60 leader carrier 27.

Above the leader is a second shiftable member or head 38 which is pinned at 39 to a pitman 40 that is adapted to be reciprocated by an adjustable crank pin as more 65 fully disclosed in my prior Patent No.

1,270,319. The shiftable head 38 is provided with an endless groove 41 and in this groove is mounted a pair of friction rollers 42 operatively connected to the truck 18 and confined between the plates 43 and 44 the latter of which is preferably integral with the truck 18, see Figure 8. The upper plate 43 is connected by a link 45 to an endless chain 46 engaging sprocket wheels 47 and 48, Fig. 1, the latter of which is driven through bevel 70 gearing 49 which in turn is operated by a shaft 50 driven through a telescoping sleeve 75 51 constituting the main shaft of the machine.

To one side of the endless groove 41 in 80 the upper shiftable head 38 and encircling the same is arranged an endless plate or strip 52 which is bolted to the shiftable head 38 in a fixed spaced relation determined by the blocks 53. The shiftable head 38 and the 85 plate 52 define a guideway for an anti-friction roll 54 carried by the truck 18 and prevent tilting of the truck 18 from its normal upright working position.

The construction above described is much 90 the same as that disclosed in my prior patents with the exception of the plate 52 which steadies the anti-friction roll 54.

It will be understood that when the main 95 shaft 51 is driven, that the truck 18 is carried around the endless groove 41 and that while it moves in this predetermined path, that the knife 9 is dragged around with it and describes a path determined approximately by the sinuous flange 25 of the leader 100 plate which is engaged by the opposed pairs of friction rolls 21-22 and 23-24.

Preferably the throw of the leader carrier is varied with every change in the size 105 of the sole to be cut, but the shiftable head 38 need have its throw varied but three times. This is effected as more fully disclosed in my prior Patent 1,270,319 through the adjustable crank pin actuating the pitman 40, it being set to a zero position to hold the 110 head 38 stationary for women's soles, with a minus throw for children's or misses' soles—i. e., to move it in a direction opposite to that in which the knife carriage is moved—and with a plus throw for men's soles, so as 115 to add its throw to that of the knife carrier. It is also to be understood that the leader carrier 27 and head 38 are both shifted at the same time excepting of course when women's soles are being cut and the latter is 120 held stationary.

The coil spring 13 which yieldingly urges the arm 10 against the form 4 and toward the stop 14 permits the knife to yield instead of digging into the form 4 whenever 125 in the operation of the machine vibration carries the knife edge 9 against it.

The main shaft 51 of the machine carries a sprocket wheel 55 which is rotated by chain 56 in engagement with an adjustable 130

treadle 84 after the stop 88 prevents further upward movement of the work table. It is also to be understood that the stop bolt 88 is preferably adjusted for a given thickness of stock so as to grip the material against the form 4 just tight enough to prevent it from shifting during the cutting operation and no more.

Different thicknesses of sheet stock will 10 require a different amount of localized pressure to effect a stamping or dieing thereof with a desired character and to this end the platen 96 is conveniently adjusted through the screws 99-99'.

15 The anti-friction roll 54, offset to one side of the tracking rolls 42, which are connected to the truck 18, is confined between the parallel faces of the head 38 and plate 52 to prevent tilting of the truck either upward or downward and thereby betters the 20 operation of the knife in traveling around the form making it steady in its inclined cutting position which causes a not considerable lateral strain.

25 The spring detent 35 for locking the leader 26 to the leader carrier 27 is also an improved feature of the present invention being quite simple and reliable in construction and operation.

30 Having thus described my invention, what I claim and desire to protect by Letters Patent is:

1. In a machine of the type described, a stationary frame carrying a form, a knife 35 and means for moving the knife around the form, in combination with a work table displaceably mounted in the frame, means limiting movement of the work table toward the form, and means including a lost motion 40 connection whereby the work table may be displaced.

2. In a machine for cutting sheet material, in combination, a knife, a form, a leader provided with a hole adjacent one edge thereof, 45 a leader carrier removably sustaining the leader, means for actuating the leader carrier and knife to move the latter around the leader, said leader carrier being provided with an opening in register with said hole 50 adjacent one edge of the leader, and a detent sustained in the hole in the leader carrier and movable transversely of the leader into the registering openings whereby the leader may be conveniently locked to the leader 55 carrier.

3. In a machine for cutting sheet material, in combination, a work table, a form, a leader spaced from the form to the side op-

posite the work table, a knife controlled by the leader, means for moving the knife 60 around the form, said last named means including a truck which is upright in the normal operation of the machine, and means for preventing any tilting of the truck from its upright position during the operation of 65 the machine.

4. In a machine for cutting sheet material, in combination, a work table, a form, a leader spaced above the form, a knife whose movement is governed by the leader, means for 70 moving the knife around the form, said last named means including a truck confined to follow a predetermined path, a shiftable head provided with a guiding groove for said truck, a guiding member on 75 said truck arranged to travel in said groove, a roller on said truck to one side of the guiding member, and a plate supported in spaced relation from and by the shiftable head for confining the roller against displacement 80 relative to the plane of the shiftable head.

5. In a machine for cutting sheet material, in combination, a form, a work table, means whereby the form and work table may be relatively shifted, a knife, mechanism for 85 moving the knife around the form, and driving mechanisms operatively connected to power and hand operable devices, said mechanisms including a one way clutch arranged to permit manual or power opera- 90

6. In a machine for cutting sheet material, in combination, a form, a work table, means for shifting the work table relative to the form, a knife, means for moving the knife 95 around the form, power driven devices for operating the machine, and a manually operable mechanism including a one way clutch ineffective when the machine is driven by power. 100

7. In a machine for cutting sheet material, in combination, a form, a work table, means for relatively shifting the form and work table to facilitate the introduction of work, a knife, means for moving the knife around 105 the form, and driving mechanism including a main shaft, an endless transmission device for driving the main shaft, a one way clutch in operative engagement with said endless transmission device, and devices capable of 110 power and hand operation enabling the machine to be operated at will by either power or hand.

Signed at Medford Mass., this 29th day of October, 1919.

ERNEST L. PATTEN.
